FORNIA.

CAN-TOP-FEEDING DEVICE.

Specification of Letters Patent. Patented Dec. 18, 1917.

1,250,406.

Application filed January 14, 1916. Serial No. 72,058.

To all whom it may concern:

Be it known that we, RAY O. WILSON and ARTHUR D. SUMNER, citizens of the United States, residing at Los Angeles, in the county of Los Angeles and State of California, have invented new and useful Improvements in Can-Top-Feeding Devices, of which the following is a specification.

Our invention relates to a mechanism for feeding can tops and is particularly adapted to be used upon a can seaming machine in which the cans are fed in an upright position.

It is an object of our invention to provide a mechanism for automatically feeding a can top to a can as it passes beneath the can top magazine.

It is another object to provide a mechanism for the purpose described which is operated by the can previous to the time when it passes under the top magazine and which positively provides that a can top will be in readiness to be fed to the can when the can passes thereunder, as long as a supply of can tops remains in the magazine.

It is a further object to provide a mechanism which makes it impossible for a top to be fed out of the magazine unless a can is in its course of travel thereunder thus making it impossible for a number of tops to be dropped from the magazine when there are no cans passing through the machine.

Another object is to provide a positive mechanism for holding the can top support in place and returning them to their closed position after a lid has been released without the aid of springs or any mechanism that might prove unreliable.

A further object is to provide a support for the can tops in the magazine which holds them in a horizontal position and which may be quickly released and again closed beneath the can without the stack of can tops being wedged or tilted and endangering their binding and choking the can top feed.

In the type of can machine disclosed the can top is not directly placed upon the can when it passes beneath the magazine but travels in a passage a short distance above the can parallel with the latter and after the can has traversed a part of its arc of travel the can supporting floor raises and

advances the can into contact with the can top thereabove and pressing the contents down into the can before sealing. An object of this invention is to provide means for engaging the can top when it is exactly above the can for which it is intended, and carrying it over the can and delivering it thereto at the time that the can rises to receive it, the top having not been misplaced during transit but exactly registering with the can at the appointed meeting place.

It is another object to provide a positive mechanism for feeding a can top to a can by its individual selection without any complicated mechanism but by a few parts which are so arranged as to have slight wear and are not easily broken and may readily be replaced.

Other objects will appear hereinafter.

The invention is illustrated in the accompanying drawings in which:

Figure 1 is a plan view of one of the can carrying drums of a double seaming machine of the vertical type showing our can top feeding mechanism as applied.

Fig. 2 is a view in elevation showing the can top feeding mechanism.

Fig. 3 is a view drawn on the same scale as Fig. 1 showing the can top feeding mechanism with all immaterial parts omitted.

Fig. 4 is a view showing the manner in which the tops are held within the magazine and passage of a can thereunder.

Fig. 5 is a fragmentary perspective view illustrating one of the can engaging lugs.

More specifically, 10 indicates a rotatable horizontally disposed can receiving member of the type in common use on a can machine in which the cans are passed through the machine in an upright position. This can receiving member is formed with acute recesses 11 spaced equidistant around its periphery, the recesses 11 having a radius substantially corresponding to that of the can which is adapted to be seamed in this machine. Mounted upon the upper face 100 of the member 10 and adjacent the rear edges of recesses 11 is a can top engaging lug 12, which extends above the face of the member 10 and is adapted to engage and dislodge the lowermost can top as it passes beneath the can top stack.

A can top feeding mechanism 13 is suitably mounted upon the machine in such manner as

ner that its center will be directly over the peripheral edge of the member 10 and on a line at right angles to the main axis of the seaming machine. This mechanism consists primarily in frame 14 approximately circular in shape and held in a horizontal position, it being here shown as bolted to a bracket 15 formed on the main portion 16 of the seaming machine. Mounted upon the frame 14 and placed equi-distant around its circumference are four brackets 17, 18, 19 and 20 adjustably secured by means of bolts 21 passing through slots 22. These brackets are arranged to project toward the center of the frame 14 and have mounted in their inner projecting ends vertical rods 23 between which the can-tops are intended to pass. An adjustable hopper or magazine for the can tops is thus provided. The frame 14 is formed at its one side with an extension 24 so formed as to form sliding bearings 25 for a portion of the top feeding mechanism.

The top feeding mechanism consists of three blades 26, 27 and 28 which are adapted to slip under the stack of can tops and hold them out of the path of travel of the can top engaging member 12. Blades 26 and 28 are formed upon arcuate portions 29 of levers 30, said levers being pivotally mounted upon extensions 31 formed upon the projecting lower ends of the rods 23. The levers extend rearwardly as indicated at 32 and are connected by pins 33 to links 34 the opposite ends of said links being pivotally connected by a pin 35 to an actuating lever 36, the actuating lever 36 being in the form of a bell crank having legs 37 and 38 and being pivotally mounted upon pin 39 secured within the bracket 40, said bracket being formed integral with the frame 14. The blade 27 is mounted upon a reciprocating bar 41 which moves through the bearings 25 by reason of its engagement with the pin 35. It will thus be noted that the movement of the bell crank 36 will tend to oscillate the bar 41 and at the same time actuate the toggle movement comprised of the links 34 and levers 32 and will in turn cause all of the blades to swing in and out from beneath the stack of can tops in the magazine.

The movement of the actuating lever 36 is positively afforded by two mechanisms, one actuated by the movement of the can and a return movement by a positive mechanism mounted upon the body of the machine. The first mentioned means consists of a lever arm 43 rigidly secured to the pin 39 and extending in a direction away from the feed magazine and having its longitudinal axis substantially parallel to the tangent of the path of travel of a can. In the end of the lever 43 is adjustably mounted a rod 44 which is secured by a set screw 45, said rod extending at right angles to the body of the lever. Upon the end of the rod is positioned

a wiper 46 having an arcuate face 47, said wiper being adapted to normally extend through the guard-rail 48 against which the can bears and into the path of travel of the can. When the can is advanced along the guard-rail 48 it encounters the arcuate face of the member 46 and gently forces it out of its path of travel. In so doing the lever 43 is moved and this in turn moves the actuating lever 36 thus forcing the bar 41 to move away from the can magazine and at the same time causing the knives 26, 27 and 28 to withdraw from beneath the can tops. It will be seen that this movement allows the stack of can tops to fall and in so doing the lowermost can top encounters shelves 49 and 50 which lead into grooves 51 and 52 within the can top conveying chute 53. The lowermost can top rests upon the aforesaid shelves until the lug 12 comes into engagement therewith. They then carry it along the chute 53 until it comes into contact with the can at 54 as described.

In our can feeding device we have shown no spring mechanism to cause the blades to again position themselves beneath the can top hopper thus withholding the tops but have provided a positive means for producing this result, said means consisting of a reciprocating arm 55 which travels back and forth through a bearing 56 mounted beneath the frame 14. In one end of said arm is a set screw 57 adapted to be locked by a nut 58, the head of said screw bearing against the inner face of the leg 38 of the actuating lever 36. The opposite end of the arm 55 is forked as at 58' and adapted to straddle the vertical shaft 59 upon which the revolvable member 10 is mounted. Positioned beneath the forked portion of the arm 55 is a cam member 60 formed with four swells 61, 62, 63 and 64 thereon. A pin 65 is mounted upon the arm 55 and projects down into the path of travel of the cam 60 so that four times in each revolution the oscillating arm 55 is moved against the arm of the actuating lever and tends to force the knives beneath the stack of can tops above the lowermost top. The inner edges of the blades 26, 27 and 28 are beveled outwardly and upwardly from their lower faces, so that when the stack of tops drops to the shelves 49 and 50 the blades 26, 27 and 28 immediately close and enter the groove above the lowermost can top and separate and raise the stack 120 therefrom before the lug 12 reaches the lowermost top. The wiper 46 opens the blades 26, 27 and 28 and the cam member 60 closes the blades before the can reaches the vertical plane of the can tops, so that the lowermost top is free from the stack at the time the lug 12 comes along. In this way it will be assured that immediately after each can top has been separated from the stack and after each can has passed under the maga- 130

zine and withdrawn its top, the magazine will be locked so that no other tops will drop until caused to do so by a can.

In the operation of this device the can is delivered from any suitable can feeding mechanism here indicated by the numeral 66 and is then engaged within one of the arcuate recesses 11 formed around the periphery of the member 10 and is then carried in a circular course of travel around one side of the shaft 59, it being held in position within the recess by the guard-rail 48. As the can advances it encounters the wiper plate 46 causing it to move out of its path of travel and operate through the levers 43 and 36 to actuate the toggle joint and oscillating bar which withdraws the three knives from beneath the stack of tops, this allowing one can top to fall upon the shelves 49 and 50. The can presently passing under the magazine is followed by the can top engaging lug 12 which encounters the waiting top and carries it around the chute 53 where it falls 54 upon the can which has been raised for this purpose by means herein not shown or described. The cam 60 has its swells so positioned that directly after a top has been released by the blades the reciprocating arm 55 operates to swing the actuating lever 56 and forces the blades beneath the stack of tops in the magazine, before the lug 12 arrives, and forms a support therefor to prevent the can tops falling into empty recesses 11 and to hold the lowermost can top clear of the can top engaging and advancing lug.

We claim—

1. In a device for delivering can tops and cans coincidently, a revoluble disk formed with can receiving depressions on its periphery, a pair of curved rails arranged above the disk on each side of the edge thereof, a can top rack, means controlled by a can being advanced by the disk for delivering a can top to the curved rails, and a finger on the disk for engaging the delivered can top and conveying it on the rails directly above the can carried by the disk.

2. A mechanism for delivering can tops and cans coincidently, comprising a horizontal disk formed with can receiving depressions on its periphery, a rack adapted to receive a stack of can tops, a pivoted blade forming a support for the can tops, means operable by a can in the disk for rocking the blade to release a can top, and a finger on the disk for engaging the released can top and moving it from beneath the stack.

3. A mechanism for delivering can tops and cans coincidently, comprising a horizontal disk formed with can receiving depressions on its periphery, a rack adapted to receive a stack of can tops, a pivoted blade forming a support for the can tops, means operable

by a can in the disk for rocking the blade to release a can top, a finger on the disk for engaging the released can top and moving it from beneath the stack, and means for restoring the pivoted blade beneath the stack.

4. A mechanism for feeding can tops, comprising a can top rack adapted to receive a stack of can tops, a pair of pivoted blades arranged to extend beneath the stack of can tops, a reciprocal blade positioned to extend beneath the stack of can tops intermediate the pivoted blades, and means for coincidentally advancing and retracting the pivoted blades and the reciprocal blade. 80

5. A mechanism for feeding can tops, comprising a can top rack adapted to receive a stack of can tops, a pair of pivoted blades arranged to extend beneath the stack of can tops, a reciprocal blade positioned to extend beneath the stack of can tops intermediate the pivoted blades, and means for retracting the blades controlled by a can for releasing a can top.

6. A mechanism for feeding can tops, comprising a can top rack adapted to receive a stack of can tops, a pair of pivoted blades arranged to extend beneath the stack of can tops, a reciprocal blade positioned to extend beneath the stack of can tops intermediate the pivoted blades, means for retracting the blades controlled by a can for releasing a can top, and means for automatically advancing the blades after the release of a can top. 100

7. A can top feeding mechanism comprising a rack adapted to receive a stack of can tops, a pair of pivoted levers, blades on the outer ends of said levers adapted to extend beneath the stack of can tops, a reciprocal bar, a blade on said bar positioned to extend beneath the stack of can tops intermediate the other blades, toggle links connecting said levers to said bar, and means for reciprocating said bar to coincidentally advance and retract the blades. 105

8. A can top feeding mechanism, comprising a rack adapted to receive a stack of can tops, a pair of pivoted levers, blades on the outer ends of said levers adapted to extend beneath the stack of can tops, a reciprocal bar, a blade on said bar positioned to extend beneath the stack of can tops intermediate the other blades, toggle links connecting said levers to said bar, and means for reciprocating said bar to coincidentally advance and retract the blades, comprising a bell crank lever connected to the reciprocal bar, means controlled by a can for rocking said lever in one direction, to retract the blades, and separate means for rocking the bell crank lever in the opposite direction to advance the blades. 120

9. A can top feeding mechanism, comprising a rack adapted to receive a stack of can tops,

can tops, a pair of pivoted levers, blades on the outer ends of said levers adapted to extend beneath the stack of can tops, a reciprocal bar, a blade on said bar positioned to extend beneath the stack of can tops intermediate the other blades, toggle links connecting said levers to said bar, and means for reciprocating said bar to coincidentally advance and retract the blades, comprising a bell crank lever connected to the reciprocal bar, means controlled by a can for rocking said lever in one direction to retract the blades, a reciprocal bar engageable with said bell crank lever, a rotary shaft, and means 10 on said shaft for advancing said bar to

actuate the bell crank lever to advance the blades.

10. In a can top feeding mechanism, a reciprocal blade, a pair of pivoted blades arranged on opposite sides of the first-named 20 blade, said blades forming a support for a stack of can tops, and means whereby advance or retracted movement of the reciprocal blade will operate to advance or retract the pivoted blades coincident therewith. 25

In testimony whereof we have signed our names to this specification.

RAY O. WILSON.
ARTHUR D. SUMNER.
